CLIMBING ATTACHMENT FOR SKIS

Ernest Lapointe, Magog East, Quebec, Canada

Application June 10, 1949, Serial No. 98,280
In Canada March 31, 1949

3 Claims. (Cl. 280—11.37)

1

The present invention relates to a climbing attachment for skis.

More specifically, this invention concerns an attachment affixable to skis which may be adjusted to an operative position under the ski for use in climbing, etc., or to an inoperative, out-of-the-way position.

It will be recognized that skiers often have difficulty in climbing steep or icy slopes owing to the tendency of the skis to slide downward. 10 Many skiers thus are caused awkward and even dangerous tumbles.

It is the main object of the present invention to provide an attachment which the skier may adjust on his skis when climbing or standing still, 15 the said attachment being adapted to discourage the ski from slipping when the skier exerts pressure thereon.

Another important object of the invention is to provide an attachment of the character described which is simple and practical in design, and which may advantageously be fitted to any conventional type of ski.

Yet another object is to provide an attachment such as is set forth above which is easily and inexpensively constructed and may be modified quickly for use in different kinds of snow.

And still another object is to provide an attachment of the nature described which may act also as a guide for some types of ski-boot harnesses, for instance, the cable-type of harness.

Other objects and advantages will become apparent, or be further pointed out, in the description to follow.

As an example, and for purposes of illustration only, a preferred embodiment of my invention is shown in the annexed drawing, wherein:

Figure 1 shows a perspective view of the attachment in inoperative position affixed to a ski;

Figure 2 shows a similar view but with the attachment adjusted into operative position as when climbing;

Figure 3 shows an enlarged perspective view of the attachment only, as adjusted corresponding to Fig. 1;

Figure 4 shows a similar view with the device adjusted as in Fig. 2;

Figure 5 shows a side elevation view of a portion of the ski looking at one end of the device when adjusted operatively;

Figure 6 shows a section transverse the ski corresponding to line 6—6 in Figure 5, and

Figure 7 shows a section taken along line 7—7 of Figure 6.

Referring now to the drawing, wherein the 55 inoperative position across the top of frame

2

same reference characters indicate corresponding parts throughout, the device is seen to comprise a plate 10 transverse the ski and swingable in a transverse plane, the said plate being coupled to a frame 11 (fixed across the top of the ski) and being capable of fixture in an inoperative position across the ski above frame 11 or in an operative position transverse the bottom of the ski jutting downward therefrom. Obviously in the former position the attachment has no effect on the action of the ski, but in the latter position plate 10 juts down into the snow or ice footing and holds the ski against slipping unless the same is lifted as the wearer steps onward.

The drawing shows in detail a preferred manner of mounting plate 10 with respect to the ski and in co-operation with frame 11. The latter comprises a pair of spaced parallel bars 12 mounted transverse the ski (extending somewhat laterally thereof) on a central plate 13 and held as by screws 14. At each end thereof, the bars are enlarged in an upwardly direction relative to the ski and have a pin 15 mounted therein. Near the base of the bars, a pivot pin 16 is mounted therebetween at one end and projecting lugs 17 are provided on the other and for reasons hereinafter set forth.

Upon pin 16 is journaled, at one end, a link member designated by 19 which is accordingly swingable in a plane transverse to the ski. The other end of the link carries a sleeve 20 through which passes a pin 21. The link is preferably of hollow cylindrical shape and has a spring 22 coiled therein. A shaft 23 which carries sleeve 20 at one end is slidable in the link and is coupled to spring 22 in order that the sleeve will be urged in towards the link.

Another link 25, of dimensions corresponding to the first, is releasably securable to projecting lugs 17 of the frame by virtue of a wing-bolt 26, the winged head of which projects from the link and may be engaged on the lugs. At the other end of the link is a sleeve 27 carrying a pin 28 and being carried, in turn, by a shaft 29 urged inwards relative to the link by a spring 30, just as in the case of link 19.

The plate 10 is in a plane transverse the ski and is carried on a perpendicular bar 31. At each end of the bar are a pair of ears 32 by virtue of which the plate is pivotally coupled on pins 21 and 28. Accordingly, if the wing-bolt be disengaged from lugs 17, plate 10 and the two links may be swung back and forth around the ski so that the plate may occupy, selectively, a limit-

11 or a limiting operative position across underneath the ski. In each case, to hold the device in position, the body of the wing-bolt is adjusted between the lugs 17 with the winged head engaged on the latter. In these positions, the depth of the ski or the height of bars 12 cause sleeves 20 and 27 to be drawn somewhat away from the respective ends of their links against the force of the springs. The tension of the springs holds the wing bolt from inadvertent disengagement.

Obviously operation or adjustment of the device is simple. To move the plate 10, the skier disengages the wing bolt and swings the device into the desired position, re-engaging the bolt once more. If desired, different types of plate 10 may be provided for different types of snow. For icy conditions, a plate 10 having downwardly directed teeth 35 reinforced by gusset plates 36 is preferable. For thick soft snow, a straight plane plate may be desirable. To change plates, pins 21 and 28 may be rendered removable, perhaps each being threaded in one lug 32.

As another feature of the invention, the device may frequently be located in front of the skier's boot when the latter is using a harness of the cable type, or a similar style.

In such cases, the spring cables (38, Figs. 2, 6) may be only very loosely controlled and the invention may act also as a guide for same. In this case, Figure 6 shows that the bottom of bars 12 are provided with notches 39 through which the cables may be passed for guiding purposes. Where the skis are of the type having a ridge 40 in the middle thereof at this point, angle bars such as 41 may be affixed to the skis under bars 12 in order to provide a flat surface upon which cables 38 may slide and also to provide a closure for the bottom of notches 39.

Obviously, from the foregoing, the present invention fulfills the objectives set forth above. When constructed of magnesium the device constitutes an exceedingly light, simple and effective attachment for assistance to a skier in climbing, etc. It is easily adjusted, the snow or ice-gripping plate may easily be exchanged for varying snow conditions, and the device may be manufactured at low cost. Finally, the device may act also as a guide for the cables of certain types of ski equipment.

It will therefore be understood that I do not 50 limit myself to the particular embodiment of my invention herein shown and described, since obviously various alterations may be made in the size, shape and arrangement of parts, without departing from the spirit of the invention or the scope of the subjoined claims.

Having thus described my invention, what I claim is:

1. In a ski attachment of the character described, a frame affixable across the ski extending laterally thereof, an extensible resilient link

at each end of the frame, one of said links pivoted to the frame and the other link having means for releasably and resiliently securing it to said frame, said securing means comprising a pair of lugs projecting out from one end of said frame and a wing-bolt on the corresponding link, the body of said bolt adapted to fit between said lugs and the winged head adapted to engage same, and a plate for snow-gripping purposes pivoted at each end to one of said links; whereby said links and plate may be swung in a plane transverse the ski and selectively fastened so that said plate occupies an inoperative position across the top and an operative position across the bottom of the ski.

2. In a ski attachment of the character described, a frame affixable across the ski extending laterally thereof, an extensible resilient link at each end of the frame, each comprising a cylindrical hollow member, a rod slideable within said member and a coil spring secured at one end of said rod and bearing at the other end against said member to urge said rod inwardly of said member, one of said links pivoted to the frame and the other link having means for releasably and resiliently securing it to said frame, said securing means comprising a pair of lugs projecting out from one end of said frame and a wing-bolt on the corresponding link, the body 20 of said bolt adapted to fit between said lugs and the winged head adapted to engage same, and a plate for snow gripping purposes pivoted at each end to one of said links, whereby said links and plate may be swung in a plane transverse the 25 ski and selectively fastened so that said plate occupies an inoperative position across the top and an operative position across the bottom of the ski, the thickness of the ski and of the frame being such, relative to the normal length of the 30 links, as to force the plate away from the links and hence place a strain on said springs when the device is fastened in operative and inoperative positions, the tension on said springs adapted to prevent in turn inadvertent disengagement of said wing-bolt from said lugs.

3. In a ski attachment as claimed in claim 2, said frame having apertures therethrough adapted to pass ski cables and guide the same.

ERNEST LAPOINTE.
